(57) **CLAIM**

The ornamental design for an electric scooter as shown and described.

DESCRIPTION

FIG. 1 is a perspective view of an electric scooter showing the new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view taken from the encircled area 9 of FIG. 1;

FIG. 10 is an enlarged detail view taken from the encircled area 10 of FIG. 1;

FIG. 11 is an enlarged detail view taken from the encircled area 11 of FIG. 2;

FIG. 12 is an enlarged detail view taken from the encircled area 12 of FIG. 2;

FIG. 13 is an enlarged detail view taken from the encircled area 13 of FIG. 3;

FIG. 14 is an enlarged detail view taken from the encircled area 14 of FIG. 3;

FIG. 15 is an enlarged detail view taken from the encircled area 15 of FIG. 4;

FIG. 16 is an enlarged detail view taken from the encircled area 16 of FIG. 5;

FIG. 17 is an enlarged detail view taken from the encircled area 17 of FIG. 5;

FIG. 18 is an enlarged detail view taken from the encircled area 18 of FIG. 6;

(Continued)

FIG. 19 is an enlarged detail view taken from the encircled area 19 of FIG. 6;

FIG. 20 is an enlarged detail view taken from the encircled area 20 of FIG. 7;

FIG. 21 is an enlarged detail view taken from the encircled area 21 of FIG. 8; and,

FIG. 22 is an enlarged detail view taken from the encircled area 22 of FIG. 8.

The broken lines shown in the figures are for the purpose of illustrating portions of the electric scooter and form no part of the claimed design.
